UNITED STATES PATENT OFFICE.

LEOPOLD BAKKE, OF CHICAGO, ILLINOIS.

PRINTING-PRESS.

1,096,589.

Specification of Letters Patent. Patented May 12, 1914.

Application filed November 1, 1913. Serial No. 798,630.

To all whom it may concern:

Be it known that I, LEOPOLD BAKKE, a citizen of the United States, and a resident of Chicago, in the county of Cook and State 5 of Illinois, have invented certain new and useful Improvements in Printing-Presses, of which the following is a full, clear, and exact specification.

My invention is concerned with presses 10 of the type in which a rocking platen is associated with a swinging bed-plate, so that during a portion of the cycle of operation, the platen is presented in proper position to have placed thereon the paper to 15 be printed, and is then swung to printing position, in which position the bed-plate is swung to print by the type carried thereby upon the paper carried by the platen. In these presses as heretofore constructed, the 20 movement of the platen has been controlled by a cam, which is subject to severe wear, and soon gets the parts out of adjustment.

By my invention, I do away with the cam, 25 substituting a link connection, and produce a mechanical movement that is simple and durable, and dispense with all the objectional features of the cam mechanism above mentioned.

To illustrate my invention, I annex hereto 30 a sheet of drawings, in which the same reference characters are used to designate identical parts in all the figures, of which,—

Figure 1 is a side elevation of a press 35 showing the platen in the paper-receiving position and the bed-plate retracted, in full lines, with the bed-plate and platen in printing position, in dotted lines; Fig. 2 is a side elevation of the yielding link connection shown in central longitudinal section; 40 and Fig. 3 is an enlarged detail in section on the line A—A of Fig. 2.

My invention is adapted to be applied to the customary Gordon type of press, in which the frame 10 has the drive shaft 11 45 mounted therein and rotated by any suitable source of power, this shaft carrying a spur-gear pinion 12 meshing with a spur-gear wheel 13 on a shaft 14, also journaled in the frame 10. An eccentric pin 15 on the 50 spur-gear wheel 13 has pivoted thereon a link 16, which is pivotally connected at 17 to the bed-plate frame 18, which is pivoted on the main frame 10 at 19. While the inking mechanism is shown in the drawings,

the invention is not concerned with the operation of said inking mechanism. The bed-plate frame 18 carries the customary type-bed 20, and it will be obvious that the rotation of the shaft 14 tends to bring the bed-plate first to printing position, and then 60 to retract the same for the inking operation.

Journalized in the frame 10 is a rock shaft 21, which has secured thereon the platen 22, which is swung up into the position shown 65 in full lines in Fig. 1, where it is adapted to have the paper to be printed placed thereon by hand during the time that the bed-plate is retracted for inking the type. When an impression is taken, it is obvious that the 70 rock shaft 21 must be rocked to the dotted-line position, and the frame 18 similarly swung to its dotted-line position to make the impression, and my present invention is concerned with the connections by which the 75 movement of the bed-plate frame 18 serves to swing the platen back and forth at the proper times and with proper interval between its movements.

In carrying out my invention, I secure, on 80 the rock shaft 21 an arm 23, and connect this arm with the bed-plate frame by a link, which I will designate generally by the numeral 24. The details of construction of this link are best shown in Figs. 2 and 3, 85 where it will be seen that the inner end is formed preferably of a tube 25, in which is placed a helically-coiled expanding spring 26, which tends to hold the reduced end 27 of the outer portion 28 in the position shown 90 in Figs. 2 and 3, in which position the pin 29, secured in the tube 25, and passed through a slot 30 in said reduced portion 27 is in its outermost position in said slot. The outer portion 28 is also provided with a 95 helically-coiled expanding spring 31 mounted therein and adapted to have its tension increased or diminished by a set screw 32 threaded through a nut 33 secured in the outer end of the portion 28, and coöoperating 100 with a plug 34 against which the end of the spring 31 rests. The inner end of the portion 28 preferably takes the shape of an open guide slot 35, in which the block 36 is adapted to reciprocate, said block being 105 preferably provided with a pin 37 extending into the end of the coil of the spring 31. The block 36 is held by a pivot pin 38 in its

position on the supporting bracket 39 secured to the side of type bed-plate frame 18. With the construction thus described, the operation of my novel movement is as follows: Assuming that the parts are in the position shown in full lines, in which the bed-plate frame 18 is retracted as far as possible from the platen, in this position, the block 36 occupies the outer portion of the 10 guide slot 35, and the spring 31 is compressed. As a result of the operation of this spring, when the bed plate frame 18 begins to swing toward the platen, the link 24 is held from movement until the bed-plate frame 18 has swung inward far enough 15 so that the block 36 can move to the inner end of the slot 35 under the pressure of the spring 31. This holding the link 24 from movement for this interval, increases the 20 length of time in which the platen is held in the feeding position shown in full lines in Fig. 1, so that the operator has that much more time to place the paper carefully on the platen. At the end of this movement of the block 36 in the slot 35, the further inward movement of the bed-plate frame 18 moves the link 24 inward, and as it moves, it rocks the shaft 21, bringing it ultimately down to the dotted-line printing position 25 shown in Fig. 1, and when it reaches this position the spring 26 is still expanded, with the pin 29 at the outer end of the slot 30. The taking of the impression necessitates a further inward movement of the bed-plate frame, and as the crank arm 23 and the portion 25 of the link cannot move any 30 farther, the outer portion 28 of the link continues its movement by reason of the reduced end 27 passing farther into the portion 25, compressing the spring 26 as much 35 as may be necessary to secure the desired sharpness of the impression. At the end of this inward movement, the link 16 of course begins to move outward, and this 40 carries the bed-plate frame 18 outward. When this outward movement starts, the spring 26 expands until the pin 29 rests in the outer ends of the slots 30, after which the link 24 moves as a whole, and the shaft 45 21 is rocked to swing the platen 22 to the paper-receiving position shown in full lines in Fig. 1. Toward the end of the outward movement of the bed-plate frame 18, the platen 22 is brought to the paper receiving 50 position, in which it cannot be swung any farther, after which the continued movement of the bed-plate frame 18 is permitted by reason of the block 36 moving outward 55 in the slot 35 and compressing the spring 31, as previously mentioned.

While I have shown and described my invention as embodied in the form which I at present consider best adapted to carry out its purposes, it will be understood that 60 it is capable of modifications, and that I do

not desire to be limited in the interpretation of the following claims except as may be necessitated by the state of the prior art.

What I claim as new, and desire to secure by Letters Patent of the United States, is:

1. In a press, the combination with a frame, of a driving shaft journaled therein, a swinging bed-plate pivoted on the frame, a platen pivoted on the frame, connections between the shaft and the bed-plate for 75 swinging the latter toward and from the platen, once for each rotation of the shaft, a crank arm connected to the platen, a yielding link connecting the crank arm and the bed-plate, and means for preventing the 80 movement of the crank arm during the inward portion of the movement of the bed-plate until the latter reaches a certain position.

2. In a press, the combination with a 85 frame, of a driving shaft journaled therein, a swinging bed-plate pivoted on the frame, a platen pivoted on the frame, connections between the shaft and the bed-plate for swinging the latter toward and from the 90 platen, once for each rotation of the shaft, a crank arm connected to the platen, a yielding link connecting the crank arm and the bed-plate, and means for preventing the movement of the crank arm during the inward portion of the movement of the bed-plate until the latter reaches a certain position, said means consisting of a spring that is compressed during the final portion of the outward movement of the bed-plate, and 95 whose expansion during the first portion of its inward movement prevents the movement of the link until the spring has expanded.

3. In a press, the combination with a 105 frame, of a driving shaft journaled therein, a swinging bed-plate pivoted on the frame, a platen pivoted on the frame, connections between the shaft and the bed-plate for swinging the latter toward and from the 110 platen, once for each rotation of the shaft, a crank arm connected to the platen, and a yielding link connecting the crank arm and bed-plate, and including two springs, one of which is compressed during the final 115 portion of the outward movement of the bed-plate, and whose expansion during the first portion of the inward movement prevents the movement of the link until said spring has expanded, and the other one of 120 which is compressed effectually to shorten the link at the time the impression is actually taken.

4. In a press, the combination with a 125 frame, of a driving shaft journaled therein, a swinging bed-plate pivoted on the frame, a platen pivoted on the frame, connections between the shaft and the bed-plate for swinging the latter toward and from the 130 platen, once for each rotation of the shaft,

a crank arm connected to the platen, a two-part link connecting the crank arm and the bed-plate and having telescoping connections, and a spring in said link tending to 5 keep it extended.

5. In a press, the combination with a frame, of a driving shaft journaled therein, a swinging bed-plate pivoted on the frame, a platen pivoted on the frame, connections between the shaft and the bed-plane for swinging the latter toward and from the platen, once for each rotation of the shaft, a crank 10 arm connected to the platen, a two-part link connecting the crank arm and the bed-plate and having telescoping connections, a spring in said link tending to keep it extended, and a second spring carried by the link and compressed by the connection of the bed-plate with the link at the end of the outward movement of the bed-plate to increase 15 the effective length of the link.

6. In a press, the combination with a frame, of a driving shaft journaled therein, a swinging bed-plate pivoted on the frame,

a platen pivoted on the frame, connections between the shaft and the bed-plate for swinging the latter toward and from the platen, once for each rotation of the shaft, a crank arm connected to the platen, a link connecting the crank arm and the bed-plate, 20 and comprising a tubular inner portion having a helically-coiled expanding spring therein, and an outer portion having its inner end telescoping in the outer end of the inner portion, and having a recess therein 25 adjacent its inner end, a helically-coiled expanding spring in said outer portion beyond the recess, and a block sliding in the recess in said outer portion, said block being pivotally carried by the bed-plate. 30

In witness whereof, I have hereunto set my hand and affixed my seal, this 16th day of October, A. D. 1913.
